UNITED STATES PATENT OFFICE

WINCLOW R. CHERMACK, OF HOPKINS, MINNESOTA

ROTARY HONE

Application filed November 23, 1929. Serial No. 409,351.

This invention relates to improved tools which may be conveniently entitled a rotary hone, and it has more particular reference to a structure of this type which is employed for the purpose of reconditioning the interior of cylindrical bodies, such as automobile engine cylinders, pump cylinders, and in fact cylinders of all types.

Briefly described, the invention has reference to a tool of this class which embodies, among other parts, a rotary propelling shaft provided with a plurality of circumferentially spaced eccentrically pivoted honing stones, and means of a yieldable nature for maintaining said stones in yieldable contact with the surface being treated, said means serving as an automatic adjusting and tensioning device for the stones.

I am aware of the fact that it is not broadly new to provide a reconditioning tool of this type in the nature of a structure including a honing stone. My principal aim is therefore, to generally improve upon known patented and marketed tools of the similar class, by providing one which is characterized by a novel arrangement of parts, mechanically associated and cooperating in securing the production of a more practicable tool which will fulfill the requirements of a device of this class in a highly satisfactory and efficient manner.

The specific elements, and their mechanical relationship or coordination will become more readily apparent from the following description and drawings. In the drawings:

Figure 1 is a top plan view of a hone constructed in accordance with the present invention, showing the manner in which it is used.

Fig. 2 is a longitudinal sectional view taken approximately on the plane of the line 2—2 of Fig. 1.

Fig. 3 is a detail view of the central portion of the structure including the automatically operable expanding elements.

Fig. 4 is a horizontal detail section taken approximately on the plane of the line 4—4 of Fig. 2.

Fig. 5 is a cross section on the line 5—5 of Fig. 3.

Fig. 6 is a cross section on the line 6—6 of Fig. 3.

Fig. 7 is a bottom plan view of the structure seen in Fig. 3.

Fig. 8 is a fragmentary perspective view of one of the stones.

Attention is invited to Fig. 2, wherein the general assembly may well be seen. Here, the reference character 9 designates tubular propelling shafts driven from any suitable source of power (not shown). Keyed on the shaft at longitudinally spaced points are substantially disk-like mounting plates 10 and 11 respectively. These plates are of the top plan configuration shown in Fig. 1. The swingably mounted hones generally designated by the reference characters 12, are mounted between these plates and in radially spaced relation from the concentric shafts 9.

I have found it expedient to provide a group of five of these swingably mounted hones, and each one is the same in construction and comprises a carrier including a channel-shaped holder 13 (see Fig. 4) for the wedge-shaped honing stone 14 and suitable retention clamps 15.

At opposite ends I provide outstanding lugs 16 provided with pintles 17 which are eccentrically mounted on the head plates 10 and 11 respectively, thus allowing the complete hone to swing bodily with respect to the peripheral edge portions of said plate. Incidentally, these hones are substantially self-adjusting and are maintained in constant yieldable contact with the internal surface of the cylinder 18 as seen in Fig. 1.

Moreover, the edge portions of the plates 10 and 11 are notched out to clearance for the swinging action of the hones. The carriers include inwardly projected flanges 19 formed with converging inclined edges 19 and 20 as seen in Fig. 2 which function as cams. These cammed edges are cooperable with conical expanding elements 21 and 22 slidably mounted on the shafts and engaging the edges 19 and 20 as seen in Fig. 2.

In this connection, I call attention to a coiled spring 23 which surrounds the shaft and bears at its opposite ends against the standards. I also desire to mention the dia-

metrically opposite guide slots 24 formed in the shaft.

At this time, I invite attention to Fig. 3, wherein it will be observed that the reference character 25 designates an adjusting screw which is cooperable at its opposite ends, with spider-like followers generally designated by the reference characters 26 and 27 respectively. The upper follower 10 includes a central washer 28 cooperable with the headed ends 29 of the screw, and provided with diametrically outstanding arms 30 which project through and beyond the slots and engage the narrow end portion of 15 the adjacent expander 21.

The lower end of the shaft is screw threaded as at 31 and cooperates with the screw threads formed in the central opening of the lowermost washer 32. This washer is 20 also provided with outstanding guide arms 33 to function as keys and engage the lower expander 22. It will be noted that these expanders are disposed in reversed order. Thus, the expansion of the spring serves to 25 hold the expanders in engagement with the respective followers 26 and 27 as seen in Fig. 3.

However, by adjusting the rods, the followers are drawn toward each other to move 30 the expanders 21 and 22 toward each other against the tension of the spring, thus changing their active relationship, to bring about greater or less pressure on the cam edges 19 and 20 for the respective hones.

35 The gist of the invention is in the provision of the tubular drive of propeller shaft carrying a longitudinally spaced head, constituting a honing for the eccentrically pivoted swingable carriers of the quintet of hones.

40 The natural expansion of the expanders 21 and 22 maintains a constant pressure on the flange portions of these hones, and thereby maintains the honing blocks or stones in proper contact with the interior surface of 45 the cylinder, as seen in Fig. 1. In this way, the hones are automatically adjustable and yieldably maintained in place.

45 From the foregoing description and drawings, it will be seen that I have evolved novel structural arrangements of parts, which when associated as shown and described, will fulfill the requirements of a tool of this class in a highly satisfactory and practicable manner.

50 It is thought that persons skilled in the art to which the invention relates will be able to obtain a clear understanding of the same, after considering the drawings and 55 description. Therefore, a more lengthy description is regarded as unnecessary.

55 Minor changes in shape, size, and rearrangement of elements, coming within the field of invention claimed, may be resorted 60 to in actual practice if desired.

Having thus described my invention, what I claim as new is:—

1. In a cylinder hone of the class described, a shaft, a pair of longitudinally spaced mounting plates of disk-like form 70 mounted on said shaft, a plurality of circumferentially spaced honing devices, each device comprising a holder, a stone fastened in said holder, an inwardly projecting flange having converging cam edges, a pair of outstanding lugs, pintles carried by said lugs and eccentrically pivoted in bearing openings in said plates, automatically operable expanding means cooperable with said cam edges and mounted on said shaft, and embodying a pair of shiftable longitudinally spaced spring-pressed conical expanders and 75 adjustable stops for limiting the movement of the said expanders away from each other.

2. In a cylinder hone of the class described, a shaft, a pair of longitudinally spaced mounting plates of disk-like form 80 mounted on said shaft, a plurality of circumferentially spaced honing devices, each device comprising a holder, a stone fastened in said holder, an inwardly projecting flange having converging cam edges, a pair of outstanding lugs, pintles carried by said lugs and eccentrically pivoted in bearing openings in said plates, automatically operable 85 expanding means co-operable with said cam edges and mounted on said shaft, and embodying a pair of longitudinally spaced conical expanders, a spring yieldably urging the expanders away from each other, adjustable 90 stops for limiting the movement of the said expanders away from each other, and an adjusting screw connected with said stops for adjusting the stops toward each other to bring 95 said expanders toward each other against the 100 tension of the spring.

3. In a structure of the class described, a rotary propeller shaft provided with diametrically opposite slots, a screw threaded bolt 105 arranged centrally in said shaft, a pair of longitudinally spaced followers functioning as stops and including central washers and outstanding arms, said arms projecting through and beyond the slots, a pair of conical expanders surrounding and slidable on 110 said shaft, a spring surrounding the shaft and bearing at its ends against the inner ends of said expanders in a manner to force said expanders into engagement with the arms of said followers, and a plurality of adjustable honing devices arranged circumferentially around the shaft and operatively 115 engageable by the expanders for adjustment thereby.

120 In testimony whereof I affix my signature.

WINCLOW R. CHERMACK.
